(57) **CLAIM**

The ornamental design for an eyeglass wrap, as shown and described.

DESCRIPTION

FIG. 1 is a front view of the eyeglass wrap design.

FIG. 2 is a rear view of the eyeglass wrap design.

FIG. 3 is a top view of the eyeglass wrap design.

FIG. 4 is a bottom view of the eyeglass wrap design; and,
FIG. 5 is a right side view of the eyeglass wrap design. The left side view is a mirror image of the right side view.

Any broken lines utilized in the figures are for environmental purposes only and form no part of the claimed design. Viewpoints not illustrated present no additional ornamental features over those illustrated in the present set of drawings.
